CLAIM

The ornamental design for a quick-release ENT surgical holder, as shown and described.

DESCRIPTION

FIG. 1 is a perspective view of a quick-release ENT surgical holder, showing our new design;

FIG. 2 is a front elevational view thereof;

FIG. 3 is a rear elevational view thereof;

FIG. 4 is a left-side elevational view;

FIG. 5 is a right-side elevational view;

FIG. 6 is a top plan view of the quick-release ENT surgical holder, showing our new design;

FIG. 7 is a bottom plan view thereof;

FIG. 8 is a view of the quick-release ENT surgical holder of our design in conjunction with a first type of flexible arm positioner; and,

FIG. 9 is a view of the quick-release ENT surgical holder of our design in conjunction with a second type of flexible arm positioner.

The broken line showing of the flexible arm positioner in FIGS. 8 and 9 is for illustrative purposes only and forms no part of the claimed design.
